TUBE FURNACE FOR HEATING

BACKGROUND OF THE INVENTION

This invention relates to a tube furnace for heating, particularly a tube furnace for heating which performs principally the pyrolysis of hydrocarbons, particularly of ethane, propane, naphtha, kerosene, light oil, gas oil and the like, into olefins, diolefins, aromatic hydrocarbons and the like.

In the past, one type of furnaces widely in use for this purpose is the so-called horizontal tube furnace or a heating furnace of the construction in which a large number of short-flame burners are arranged through the sidewalls of the furnace, and a nest of pipes are horizontally supported in the center of the radiant section consisting of the sidewalls, ceiling, bed and front and rear walls, and a convection section for the recovery of waste heat located above the radiant section. In the furnace of the type described, short-flame burners of flat flames must be used for uniform heating of the pipes and for keeping the flames from direct contact with the pipes. In addition, the relatively small capacity of the individual burners necessitates the use of a large number of burners, thus adding complicacies to the operation and maintenance of the equipment to disadvantage. The short-flame burners use mainly gaseous fuels in order to hold the flat flames and avoid damaging of the pipes due to scatter of sludge. This not only puts extreme restrictions to the use of less expensive fuels such as heavy oil and other oils as cracking residues but also tends to cause clogging of the burner tips with impurities in the fuel or deformation of the burner tiles due to coking of the fuel oil, which in turn can affect the flame shape and induce local overheating of the pipes. Further, it is often the case with a furnace of this type that the horizontal pipes wave or sag because of creep strain or deformation by thermal stress, accompanied by corresponding deformation or damaging of the pipe fittings.

Another variety of conventional furnaces consists of a bed, sidewalls, a ceiling, and front and rear walls which altogether constitute a radiant section, a plurality of burners arranged on the bed and sidewalls, a nest of pipes suspended vertically in the center of the radiant section, and a convection section for the recovery of waste heat that is located above and alongside the radiant section. Since the furnace of this construction employs upwardly directed long-flame burners and vertically suspended pipes, it is advantageous over the first variety of conventional furnaces above mentioned in respect of the capacity and quantity of the burners and because of less possibilities of deformation and damage of the pipe fittings. However, the upwardly directed burners may cause coking of the burner tiles and, in extreme cases, they may even lead to poor distribution and leakage of the fuel oil out of the furnace with the danger of catching fire. The suspended pipes render it difficult to provide the convection section of the furnace immediately above the radiant section and, therefore, the convection section must be located alongside or above and along the radiant section. Thus if the pressure inside the furnace is increased the flames in the radiant section are attracted toward the direction of the flue of the convection section. This is a frequent cause of damage, local overheating or uneven heating of the heat transfer pipes of the convection section. Among other disadvantages of the conventional furnaces are high erection cost and inconvenience in operation and maintenance due to the fact that the heavy convection section is located at the furnace top.

SUMMARY OF THE INVENTION

An object of the invention is to provide a new vertical tube furnace for heating which is free of the foregoing disadvantages of the conventional furnaces.

Another object of the invention is to provide a vertical tube-type heating furnace which attains higher product yields than by conventional equipment of this type and which is, moreover, economical and easy to operate, maintain and control.

Another object of the invention is to provide the furnace construction such that a radiant section and a convection section are defined, respectively, in the upper and lower parts of the furnace, the two sections being separated by a heat-insulating reflecting plate formed with passages therethrough, and pipes or a nest of pipes are vertically suspended in the radiant section, and a plurality of downwardly directed burners are arranged through the ceiling and sidewalls, and an exhaust port for the flue gas is formed open in the lower part or alongside the convection section.

A further object of the invention is to provide a heating furnace has extensive applications not merely for the pyrolysis of hydrocarbons but as a chemical reaction furnace for effecting endothermic reactions.

Now a preferred embodiment of the heating furnace of the invention will be described hereunder in connection with the accompanying drawings.

BRIEF DESCRIPTION OF THE DRAWING

FIG. 1 is a section on the line 1—1 in FIG. 2 of a tube furnace for heating according to this invention.

FIG. 2 is a section on the line II—II in FIG. 1.

DETAIL OF THE INVENTION

Throughout the FIGS., numeral 1 designate the framework of the furnace body, and 2 designates sidewalls of the furnace body that are combined with front and rear walls 3, a ceiling 4, a bed 5, and a heat-insulating reflecting plate 6 to constitute a radiant section 7. Along the section of the radiant section 7 that connects the vertical bisectors of the front and rear walls there are suspended a nest of vertical pipes 8 in zigzag or coiled fashion inside the radiant section by means of hangers 10 which are equipped with spring hunger 9 and disposed through the ceiling 4. Said spring hunger 9 has a operation to be absorb thermal-deformation of pipes 8. A plurality of flat flame-shaped burners 11 are provided through the ceiling 4 and are so positioned as to give off as long downward flames as possible along the side walls 2. Also, along a horizontal line in the middle part of the sidewalls, there are a plurality of flat flame-shaped burners 12 which are adapted to produce downwardly directed flames along and close to the sidewalls, thereby to cooperate with the ceiling burners 11 to heat the sidewalls 2 to a red hot state, so that the nest of pipes 8 can be uniformly heated by the heat of radiation from the sidewalls 2 and the burner flames. To facilitate the installation of the sidewall burners 12, the portions near the middle parts of the sidewalls has shoulder-portion 13 as shown in FIG. 1, though it is not essential where the requirements for heating the sidewalls as above stated are met adequately. Between the heat-insulating reflecting plate and the bed 5 there are formed a plurality of gas passages 14, through which combustion gas from the radiant section 7 flows down into the convection section 15. The convection section 15 is defined by opposing sidewalls 16, front and rear walls 3, the heat-insulating reflecting plate 6, and bottom plate 17. In the upper space of the convection section there are provided, horizontally in a zigzag or coiled fashion, pipes 18 for preheating material hydrocarbons in communication with the inlet end of the nest of pipes of the radiant section 7. Beneath the preheating pipes are laid water pipes 19 in a similar arrangement. Said water pipe 19 has a operation for preheat a water to be fed to a quick cooling heat exchanger 24. The furnace is also provided with a flue 20 for the combustion gas, an exit 21 for waste gas, an inlet port 22 for material hydrocarbons, and an outlet 23 for the pyrolyzed gas, which communicates to a quick cooling heat exchanger 24 mounted on the furnace top above the ceiling 4 of the convection section.

In the heating furnace of the above construction, the hydrocarbons to be processed are charged through the inlet port 22 of the convection section into the preheating pipes 18, and, as it passes through the pipes, the charge is heated 75 through heat exchange with the waste combustion gas from

the radiant section 7 to an optimum temperature for the initiation of pyrolysis. The charge then flows up and down in a zig-zag fashion through the vertical pipes 8 of the radiant section 7, while being rapidly heated mainly by the heat of radiation from the sidewalls 3 heated to a red hot state by the ceiling and sidewall burners 11, 12 as well as by the long downward flames from those burners and thereby completing the pyrolytic reaction as desired. The resultant is flown through the pipe outlet 24 into subsequent components such as the quick cooling heat exchanger 24. On the other hand, the combustion gas from the flat long-flame burners 11, 12 in the radiant section 7 flows downward along the nest of pipes 8 and the sidewalls 2, into the convection section 15 through the passages 14 formed between the heat-insulating reflecting plate 6 and the bed 5. After the exchange of heat with the pre-heating pipes 18 and water pipes 19, it is led through the flue 20 and is finally exhausted out as from a stack not shown.

With the construction described above, the tube furnace for heating in accordance with this invention has a number of advantages as enumerated below:

1. Even if burners of increased capacity are used, the flames in the radiant section form parallel flows with the nest of pipes, thus avoiding direct contact of the flames with the nest of pipes. Therefore, the number of burners required may be

sections and one convection section.

6. Because the burners are mounted high, the chance of any heavier-than-air combustible gas finding its way from the outside into direct contact with the flames inside the furnace is slim, and thus a high degree of safety is ensured.

An example of ethylene pyrolysis with a heating furnace in conformity with this invention will be given below.

The heating furnace used was a vertical tube furnace embodying the invention consisting of a furnace body 2.9 meters wide, 4.7 meters long, and 9.6 meters high. It had 12 flat flame-shaped burners through the ceiling and 10 such burners through the sidewalls. In this furnace was pyrolyzed naphtha having a specific gravity of 0.7012 (at 15/4° C.) and a mean molecular weight of 98. The starting material in this case was treated at the rate of 6,200 kg. of naphtha per hour with 3,200 kg. of steam per hour. By the flat burners a heat amount of 4.3×10^6 Kcal/h was supplied to the radiant section so that the pipe inlet in the radiant section could be maintained at 560° C. and the outlet temperature of the furnace at 840° C. As the result, the composition of a pyrolyzed gas tabled below was obtained. For the burners a mixed fuel consisting of 50 percent grade C heavy oil and 50 percent ethylene-recovered waste gas composed principally of hydrogen and methane was employed.

25

Component	H ₂	CH ₄	C ₂ H ₂	C ₂ H ₄	C ₃ frac.	C ₄ frac.	C ₅ frac. ~ nonarom. arom. frac. below B.P. 180° C.	Others

reduced, and low-sludge fuels of low combustion rates, as for example grade C heavy oil and other inexpensive liquid fuels may be employed. This not merely saves the installation cost but, in addition, permits steam blowing of the burner tips, thereby rendering it possible to operate and maintain the furnace advantageously.

2. Since the burners are installed with the tips directed downward, the fuel even if poorly distributed will drop inside the furnace with no possibility of depositing on the burner tiles and forming coke thereon. Also, the fuel even if allowed to leak out of the furnace has no danger of catching fire.

3. The radiant section of the furnace is surrounded by heat-insulating ceiling, bed and side walls and also by the heat-insulating reflecting plate. Moreover, the downwardly directed long-flame burners achieve uniform radiant heat distribution. These features combine to minimize the possibilities of local overheating and coking and maintain good reaction conditions. Where the reaction pipes are filled with a catalyst, the lifetime of the catalyst can be prolonged.

4. The arrangement of the convection section underneath the radiant section and the provision of adequate passages for combustion gas between the heat-insulating reflecting plate and the bed enable the furnace to have a rectifying effect of the combustion gas. In addition, because the combustion gas uniformly flows downward, uneven heating in the convection section due to any drift convection can be avoided and the product yield is accordingly increased.

5. The relatively heavy convection section being installed at a low place, it is easy to build and maintain. Additional advantage is obtained from the viewpoint of the furnace layout if the convection section is provided below and alongside the radiant section so that the furnace is composed of two radiant

Note: 1. The proportions of the composition were calculated on the dry gas basis.
2. frac. means fraction 3. arom. means aromatic fraction

4. b.p. means boiling point

35 It will be obvious to those skilled in the art that various changes may be made in the invention without departing from the spirit and scope thereof and therefore the invention is not limited by that which is illustrated in the drawing and described in the specification, but only as indicated in the accompanying claims.

40 What is claims is:

1. A tube furnace for heating characterized in that a radiant section and a convection section are located, respectively, in the upper and lower spaces inside the furnace, the radiant section and the convection section being separated from each other by a heat-insulating reflecting plate which is formed with passages for combustion gas, pipes are vertically suspended in the radiant section and a plurality of downwardly directed burners are mounted on the ceiling and the sidewalls of the 45 radiant section, the pipes in the radiant section being communicated at one ends with the end of pipes disposed in the convection section and led at the other ends out of the furnace through the ceiling, and an exhaust port for the flue gas is formed open through the lower part of the convection section.

2. A tube furnace for heating according to claim 1 wherein 50 said burners are provided such that a flame of its flow at parallel direction to said pipes.

3. A tube furnace for heating according to claim 1 wherein 55 said pipes are disposed in a zigzag or coiled fashion.

4. A tube furnace for heating according to claim 1 wherein the water pipes which preheat water to be fed to a quick cooling heat exchanger are provided in connection section at beneath said pipes disposed in convection section.
